Primary Examiner — Antoine D Davis*(74) Attorney, Agent, or Firm* — Edward J. Baba; Bozicevic, Field & Francis LLP(57) **CLAIM**

The ornamental design for analyte sensor, as shown and described.

DESCRIPTION

FIG. 1 is a schematic perspective view of an exemplary analyte sensor, with no claim made to the portion shown in phantom; and,

FIG. 2 is a schematic top view of the analyte sensor of FIG. 1, with no claim made to the portion shown in phantom.
